UNITED STATES PATENT OFFICE.

FREDERICK C. KROEGER, OF ANDERSON, INDIANA, ASSIGNOR TO GENERAL MOTORS CORPORATION, A CORPORATION OF DELAWARE.

ENGINE-STARTING APPARATUS.

Application filed July 28, 1924. Serial No. 728,591.

This invention relates to electric switches and more particularly to switches for electric motors for starting internal combustion engines.

5 The object of the invention is to produce a starting motor switch at lower cost than of heretofore. A further object is to provide a starting switch which is particularly adapted for use with starting apparatus including an electric motor which is normally disconnected from the engine which may be connected with the engine for cranking purposes by the operation of a pedal which also controls the motor switch.

10 Further objects and advantages of the present invention will be apparent from the following description, reference being had to the accompanying drawing, wherein a preferred embodiment of one form of the 15 present invention is clearly shown.

In the drawings:

Fig. 1 of the drawings shows a fragmentary side view of an engine starting apparatus equipped with a switch embodying the 20 present invention.

Fig. 2 is a longitudinal sectional view of the switch shown in Fig. 1, and on an enlarged scale.

Fig. 3 is a sectional view on line 3—3 of 25 Fig. 2.

Referring to the drawings, 20 designates a flywheel gear of an engine to be started. 21 is a pinion adapted to mesh with the gear 20 and to be driven by an electric motor 22 30 having a field frame 23. The pinion 21 is moved into mesh with the engine gear 20 by a pedal 24 attached by rod 25 to a lever 26 which is pivoted at 27 upon a frame 28 which supports the motor field frame 23 and which 35 is adapted to be supported by the engine frame. The pedal rod 25 extends through the toe-board 30 of the automobile and is maintained in normal position shown in Fig. 1 by a spring 31 located between pedal 24 40 and a cup-shaped member 32 which surrounds the rod 25 and which is supported by the toe-board 30.

The pedal 24 controls the motor 22 through the use of a switch 40 having a plunger 41 45 located in the path of movement of the lever 26. Switch 40 includes a casing portion 42 attached by screw 43 to the field frame 23. The frame and the casing 42 comprises a switch housing for enclosing stationary contacts 44 and 45, which are engaged by a mov-

able contact 46 insulatingly supported by the plunger 41. The case 42 carries a sleeve 47 for guiding the plunger 41. Plunger 41 carries a cap 48. A spring 49 located between the case 42 and cap 48 separates the contact 46 from the contacts 44 and 45.

The contact 44 is provided by the head of the terminal bolt 50 which is insulatingly supported by the case 42 and extends through an aperture 51 in the case which is 65 larger in diameter than the bolt 50. The bolt 50 passes through a locating plate 52, a non-conducting plate 53 located inside the switch case, a non-conducting washer 54 located just outside the switch case, plain 70 metal washer 55 two permanent locking washers 56 and plain washer 57 and a nut lock washer 58. The parts 52 to 58 are provided with apertures slightly greater in diameter than bolt 50. Bolt 50 engages nut 75 59.

The contact 45 is provided by conductor 60 which is attached by a nut 61 to a field terminal bolt 62 which is insulatingly supported by the field frame 23 adjacent the left end thereof by a non-conducting block 63 located upon the frame 23, a non-conducting washer 64 located between a head 65 of the bolt 62 and the inside of the frame 23, and by two non-conducting washers 66 surrounding bolt 62 and located within an opening provided in the frame 23 for the bolt 62. Head 65 of bolt 62 is directly attached to a lead 67 of the field winding, the other lead being connected in the usual manner 80 with the insulated motor brush. The non-conducting strips 53 and 63 are less in width than the distance between the parallel sides 70 of the case 42. Two side lining members 71 of non-conducting material are located 85 against the casing side 70 and extend between the side edges of the strips 53 and 63 and interior surfaces of the side walls 70.

The head 44 of bolt 50 is provided with parallel edges 72 and 73 which are in engagement respectively with the flanges 74 and 75 of the retaining plate 52. Plate 52 has a width about equal to the distance between the lining members 71. In this manner the lining members 71 and the plate 52 cooperate to 100 prevent bolt 50 from turning when nut 59 is turned. The bolt 52 is maintained substantially concentric with the hole 51 by a lug 76 integral with the switch case 42. The lug 76 is formed by partially shearing the 105

case and bending the lug 76 from the plane of the case thus leaving an opening 77.

The switch included in the present invention is particularly adapted for manipulation by a lever pivoted adjacent one end 5 of the motor field frame, and for direct connection with a field terminal located adjacent the other end of the field frame. The switch housing provided by motor frame 23 and case 42 is substantially triangular in longitudinal section so as to provide two sides which are oblique to the third provided by the motor frame. The switch plunger, mounted perpendicular to one of these oblique sides extends obliquely 10 to the motor frame in a direction for convenient operation by the lever 26; and the switch terminal bolt, mounted perpendicular to the other oblique side, extends obliquely 15 from the motor frame in a direction diverging from the plunger so that the switch terminal is readily accessible for the application of a wrench.

While the form of embodiment of the 25 invention as herein disclosed, constitutes a preferred form, it is to be understood that other forms might be adopted, all coming within the scope of the claims which follow.

30 What I claim is as follows:—

1. A control device for an electric motor including a stationary frame having a pivoted member, comprising in combination, a stationary terminal mounted on but insulated from the motor frame, said terminal

having a portion extending away from the motor frame and toward the pivoted member; a housing adapted to fit over the said stationary terminal and to be secured to the motor frame; another stationary terminal carried by the housing; and a movable contact adapted to engage the said terminals, said contact having a plunger slidably supported by the housing so that it will lie in the path of movement of the 45 pivoted member and be engaged thereby.

2. A control device for an electric motor including a stationary frame having a pivoted member and provided with field windings, comprising in combination, a stationary terminal insulatingly supported on the motor frame and secured thereto by means of a bolt from which the terminal extends toward the pivoted member; a housing for enclosing said terminal, and provided with 50 means for securing same to the motor frame; a terminal bolt carried by the housing so that said bolt will lie directly above the bolt that secures the other terminal to the motor frame, when the housing is in 55 position on said frame; and a contact for engaging said terminals, carried by a plunger slidably supported on the housing, said plunger extending obliquely to the motor frame, toward the pivoted member and 60 in its path of movement.

In testimony whereof I hereto affix my signature.

FREDERICK C. KROEGER.
